DOUBLE-EDGED SAFETY RAZOR

Marcus B. Behrman, Brooklyn, N. Y., assignor to
 American Safety Razor Corporation, Brooklyn,
 N. Y., a corporation of Virginia

Application October 3, 1928, Serial No. 309,923

4 Claims. (Cl. 30—12)

My present invention relates generally to razors, and has particular reference to a safety-razor adapted to employ double-edged blades.

One object of my invention is to provide a safety-razor wherein the advantageous features of a blade stop engagement with the cutting edge of a blade are achieved.

It is well known that a razor will shave with maximum efficiency only when the cutting edge of the blade is properly positioned in a predetermined manner in association with a guard edge of a blade seat. Such positioning is efficiently effected by providing blade stops at opposite ends of the guard edge against which the opposite ends of the cutting edge may be made to abut.

In a single-edged razor construction, it is a comparatively simple matter to move the blade bodily up against such blade stops. In a double-edged construction, it is impossible, without severing the blade, to move both cutting edges simultaneously against respective blade stops.

It is a particular object of my invention to provide a razor designed to employ a double-edged blade wherein both cutting edges of the blade are capable of blade stop engagement without any severance of the blade.

I accomplish this general object by providing a razor wherein two opposed guard edges are themselves adapted to move toward one another so as to bring the blade stops of each into abutment respectively with the opposite cutting edges of a double-edged blade.

It is therefore a feature of my present invention to provide a safety-razor wherein a blade seat is constituted of two separate and opposed sections, these sections being relatively movable with respect to each other; and to provide means for moving these sections together in a proper manner for accomplishing the desired purpose. In one form of razor, such sections are normally spaced and are adapted to be positively moving together; while in a different form, the sections are so constructed and arranged as to be normally in close association and adapted to be spread at the desired times.

Another object of my invention is to provide a razor construction wherein the proper clamping of a double-edged blade and a proper engagement of its cutting edges with corresponding blade stops is positively assured. It is therefore a feature of my invention to provide means for clamping such a blade to the blade seat, and means for preventing the blade stop engagement from being effected until the blade is thoroughly clamped. In other words, I provide means for successively clamping

the blade and moving the blade stops into abutment with corresponding cutting edges. In one embodiment, I accomplish this by a unitary control means; in other embodiments, the clamping means is independently controllable.

The foregoing feature is of particular importance in connection with a razor conforming substantially to the customary type of razor wherein the oppositely arranged blade seat sections are angularly disposed with respect to one another so as to provide a blade seat having a generally upward-convex configuration. In a razor construction of this upwardly-convex character, my present invention is of particular value in that flexure of the blade into conformity with the seat is positively assured before the blade stops are moved together into abutment with the respective cutting edges of the flexed blade.

Another feature of my invention therefore lies in providing means for positively preventing movement of the blade seat sections toward one another until after the blade has been clamped or flexed. Or, stated otherwise, it is a feature to provide means for locking the seat sections against mutual approach as long as the clamping means is operative in clamping the blade.

More particularly, I provide at least one plug which is adapted to enter into the space between the blade seat sections and to remain in such interposition until the clamping has been accomplished. Where the clamping means includes a blade seat cover, I provide the plug or plugs as integral depending portions of the cover.

I preferably employ a pair of spaced and opposed plugs each of which is substantially T-shaped in cross-section, the stems of the T's facing one another and being adapted to enter the space between the blade seat sections.

Another feature lies in providing the plugs in such a manner as to accomplish a locking of the clamping means after the razor is ready for use. For example, I prefer to provide each plug with a portion which positions itself beneath the blade seat after the sections have closed.

Another feature lies in providing a double-edged blade of such a construction and character as to permit its ready employment with a razor of the foregoing character.

More particularly, I aim to provide a double-edged blade having an opening or openings so shaped and positioned as to permit passage therethrough of the plug or plugs or other portions of the clamping means designed to enter into the space between the blade seat sections.

For the attainment of the foregoing objects

and such other objects as may hereinafter appear or be pointed out, I have constructed several embodiments of the invention and illustrated in the accompanying drawings in which—

5 Figure 1 is an end view of one form of safety-razor embodying the features of my invention, a portion of this view being shown in cross-section;

10 Figure 2 is a cross-sectional view taken substantially along the line 2—2 of Figure 1;

Figure 3 is an exploded view of certain of the elements illustrated in Figures 1 and 2;

Figure 4 is a cross-sectional view taken substantially along the line 4—4 of Figure 2;

15 Figures 5 and 6 are views similar to Figure 4 showing different relative positions of the parts;

Figure 7 is a view similar to Figure 1 showing a modified type of razor;

20 Figure 8 is a cross-sectional view taken substantially along the line 8—8 of Figure 7;

Figure 9 is a plan view of the blade seat of Figures 7 and 8;

Figure 10 is a view similar to Figure 9, showing an adjusted position;

25 Figure 11 is a bottom plan view of the cover of Figure 7 with a blade applied thereto, a portion of the blade having been broken away;

Figure 12 is a view in the same direction as Figure 11 with the blade seat applied to the 30 blade;

Figure 13 is an exploded cross-sectional view taken substantially along the line 13—13 of Figure 8;

35 Figure 14 is a view similar to Figure 13 showing the parts in assembled positions; and

Figure 15 is a central cross-sectional view illustrating a second modification.

Referring for the moment to Figures 1—6 and particularly to Figure 3 it will be seen that I 40 have provided a razor construction which comprises the generally upwardly-convex blade seat 20 mounted upon a handle 21, this seat being adapted to receive a double-edged blade 22, and a cover 23. The blade seat 20 is provided with 45 the two opposed seat sections 24 and 25. A guard edge 26 is provided on the section 24 and a similar guard edge 27 is provided on the section 25. Blade stops 28 are provided on the guard edge 26, and blade stops 29 are provided on the 50 guard edge 27.

In this embodiment, the sections 24 and 25 are adapted to be normally in slightly spaced relationship as shown in Figure 3, the space between the sections being defined by the slot 30 55 which extends substantially parallel to the two guard edges 26 and 27. The blade seat is provided with the recesses 31 for a purpose presently to be described; and at the midportion of the seat the slot 30 widens out to provide the medial opening 32 which is in alignment with the axis of the handle 21.

The blade 22 is provided with a cutting edge 33 adapted to overlie the guard edge 26, and a cutting edge 34 adapted to overlie the guard edge 27. The blade is also provided with a medial aperture 35 adapted to overlie the opening 32. At the midportions of the side edges of the blade 22 I provide T-shaped recesses 36 adapted to overlie the recesses 31, each of the recesses 36 65 being provided with a portion 37 adapted to overlie one of the extreme ends of the slot 30. From the standpoint of the present invention, there is no objection to the blade 22 having three aligned openings similar to the opening 70 35 so that the blade might, if desired, be em-

ployed with equal facility in connection with the well known types of double-edged razors.

The cover 23 is provided with the medially depending shank 38 threaded at its lower end 39, this shank being adapted to extend downwardly through the aperture 35 and the opening 32 into the handle 21. At the opposite ends of the cover 23, I provide depending plugs 40, each of which is substantially T-shaped in cross-section and adapted to pass through the recesses 36 and 31. Each plug 40 is provided with a stem or portion 41 which is spaced from the body of the cover 23 and which is adapted to pass through the relatively narrow recess portions 37, and thence into and through the extreme ends 15 of the slot 30.

Before describing the other features of this embodiment, I will point out that in use the blade 22 is sandwiched between the seat 20 and the cover 23, and that manipulation of a unitary 20 control means will thereafter successively clamp the blade to the seat, flexing it into conformity with the latter, and then move the seat sections 24 and 25 together to bring the respective blade stops into abutment with respective cutting edges. 25

Referring now to Figures 1 and 2 I will point out that the seat sections 24 and 25 are provided respectively with opposed depending portions 42 and 43, the latter merging at their lower ends in the portion 44. The portions 42 and 43 are constructed to constitute a sleeve through which the shank 38 may extend, and they are furthermore so constructed that the seat sections 24 and 25 are resiliently movable toward each other although normally spaced. The handle 21 is formed as a hollow member provided with the interiorly threaded portion 45 adapted to engage the threaded portion 39 of the shank 38. The handle 21 is so constructed as to be inseparably associated with the portions 42 and 43 after the device has been assembled, at the same time being 40 rotatable with respect to the portions 42 and 43. This is accomplished by providing a spring split collar or the like 46 which is mounted in a shallow annular channel provided on the portions 42 and 43 and which engages also within a shallow annular channel provided on the interior wall of the handle 21 slightly above the portion 45. 45

The portions 42 and 43 are also provided with a downwardly converging shoulder 47 adapted to 50 coat with the upwardly divergent beveled upper edge 48 of the handle 21.

In Figures 4, 5, and 6 I have shown the method of use. In Figure 4 the blade 22 has been initially sandwiched between the cover 23 and the blade seat. It is to be noted that the plugs 40 have passed through the recesses 36 and 31 and now rest within such recesses. It is to be noted further that the portions 41 of the plugs 40 have passed completely through the recess portions 37 of the blade 22 and are disposed between the seat sections 24 and 25. The handle 21 is now manipulated by rotation thereof to engage the lower threaded end 39 of the shank 38, thereby drawing the cover 23 down onto the seat and clamping the blade 22 between the cover and the seat. During this clamping operation, the seat sections 24 and 25 are positively locked against mutual approach by virtue of the interposition of the plug portions 41. These plug portions remain in such interposition until the clamping has been completed. In Figure 5 the blade has been completely flexed onto the seat and the plugs 41 have just moved out of interposition between the seat sections 24 and 25. Further turning of the handle 21 now causes the 70 75

coaction between the shoulders 47 and 48 to squeeze the seat sections together, thereby bringing the blade stops 28 and 29 into abutment respectively with the cutting edges 33 and 34 of

5 the blade. It is to be noted that there is no possibility of the blade stops missing the proper encounter with the blade edges, since the movement of the blade stops cannot be accomplished until after the blade has been properly clamped onto

10 the seat.

It will also be seen that the seat sections are drawn together above the plugs 41. The latter are thereby locked in positions beneath the seat and accidental withdrawal of the cover is thereby 15 effectually prevented. As a matter of fact, the cover or clamping means is locked to the seat until the handle is again manipulated initially to spread the seat sections and thereafter to release the shank 38.

20 In Figures 7-14 I have illustrated a modified form wherein the cover is devoid of any medially depending shank such as the shank 38. In this embodiment, the seat sections 50 and 51 are so arranged as to be normally in close proximity as shown in Figure 9. They are provided with the downwardly depending portions 52 and 53 respectively, the latter being united at their lower ends by the integral connecting portion 54. The portions 52 and 53 are so constructed that they will resiliently remain relatively close together until they are forcibly spread against the inherent resilience.

25 The handle 55 is in this case provided with the upwardly extending rod 56, the latter being provided at its upper end with a wedge in the form of an elliptical disc or head 57. The latter rests within a medial opening 58 similar to the opening 32 of Figure 3. The head 57 may be said to be eccentrically mounted upon the rod 56, and it will be understood that rotation of the handle 55 will swing the major axis of the elliptical head 57 between two positions shown in Figures 9 and 10. When this axis is parallel to the space between the seat sections as in Figure 9, the seat sections are enabled to remain close together; when the major axis is turned to 90° as shown in Figure 10, the seat sections are forcibly wedged apart. To limit the rotative movement of the handle 55 to approximately this 90°, I provide a pin 59 in the lower end of the handle 55, the pin 59 engaging within a recess 60 provided in the lower end of the portion 54.

30 In this embodiment, the cover 61 must be pressed onto the seat independently of the spreading means, but it is to be noted that the seat sections cannot spring into their normal closed relationship until after the cover has been completely and firmly applied to the seat. This is so because of the provision of the opposed pair of 35 plugs 62 carried at opposite ends of the cover 61 and provided with the inwardly directed plug portions 63 as described in connection with the first embodiment.

35 A further improvement illustrated in Figures 7-14 lies in the modified construction of recesses 64 (corresponding to recesses 31 of Figure 3) and of the plugs 62. In Figures 9 and 10 it will be observed that I have provided a pair of cut-out portions or recesses 65 at the lateral ends of each 40 recess 64. If the recesses heretofore described have been substantially T-shaped, then the modification of Figure 10 places serifs at the extreme ends of the cross-bar of the T. The plugs 62 are similarly provided with serifs 66 as shown most 45 clearly in Figure 11. The blade 67 is substan-

tially the same as the blade 22, the recesses 68 in the opposite side ends thereof being suitably shaped to provide passage therethrough of the plugs 62.

5 The provision of the serifs 65 and 66 assures proper centering of the cover when it is applied to the spread blade seat so that the plug portions 63 will more easily enter and withdraw from the narrow space between the seat sections.

10 In use, the handle 55 is rotated through 90° to 10 spread the seat sections from the normal positions of Figure 9 to the spread positions of Figure 10. Preferably, the cover 61 is then turned upside-down as shown in Figure 11, and the blade 67 is applied thereto with the plugs 62 extending 15 through the recesses 68. Thereupon, the blade seat is applied in inverted condition to the blade of Figure 11. This application of the blade seat is shown most clearly in Figure 12. It will be seen that the plug portions 63 enter freely into 20 the space between the seat sections, being guided by the engagement between the inner walls of the serifs 66 and the corresponding walls of the serifs 65. The cover is then clamped firmly down upon the seat, the seat sections being locked apart by 25 the plug portions 63 until the blade has been thoroughly clamped. After this has been accomplished, a return rotation of the handle 55 will permit the seat sections to spring together into the position of Figure 9, the corresponding blade 30 stops thereby encountering the corresponding blade edges. At the same time, the plug portions 63 are locked beneath the blade seat as shown most clearly in Figures 8 and 14.

35 Figure 13 discloses with considerable clearness the relative constructions and positions of the parts prior to the sandwiching of the blade between the cover 61 and the blade seat. The seat sections of Figure 13 are shown in spread relationship. In Figure 14 the blade has been 40 completely clamped and the seat sections have been permitted to move toward each other.

45 In Figure 15 I have shown a further modification wherein the rotative movement of the handle 55 has been supplanted by a reciprocal movement thereof. A central opening 69 similar to the opening 58 is provided at its base with the downwardly converging shoulder 70. A rod 71 corresponding to the rod 56 is provided with the downwardly converging shoulder 72 and also with the 50 head 73. Rotation of the rod 71 has no effect, but when the latter is drawn downwardly, the shoulder 72 will operate to spread the seat sections. The head 73 acts as a stop to limit this downward movement. When the handle is moved 55 upwardly, the inherent resilience of the seat sections will cause them to spring together again into the positional relationship of Figure 15.

60 In certain of the drawings, I have shown the teeth of one guard edge longer than the teeth 60 of the opposite guard edge. This is a feature of construction which may or may not be employed with facility in connection with the other features of my present invention. The different constructions and proportions of the opposite 65 guard edges, both as to length of teeth and depth of same, permits a single blade to be employed selectively for different shaving requirements. For example, one cutting edge may be relatively close to the teeth while the opposite cutting edge 70 may be relatively remote from the teeth after the blade has been clamped.

75 It will be obvious that changes in the details herein described and illustrated for the purpose of explaining the nature of my invention may be 75

made by those skilled in the art without departing from the spirit and scope of the invention as expressed in the appended claims. It is therefore intended that these details be interpreted as 5 illustrative, and not in a limiting sense.

Having thus described my invention and illustrated its use, what I claim as new and desire to secure by Letters Patent is—

1. In a safety-razor, a blade seat comprising 10 a pair of opposed and relatively movable sections, a guard edge on each section, and blade stops on each guard edge; resilient means for normally holding said sections together, means for spreading said sections, means for clamping 15 a double-edged blade to the seat while the sections are spread, and means for locking said sections in spread relationship until the clamping has been accomplished, said last-named means comprising a plug carried by the clamping 20 means and adapted to enter the space between said sections.

2. In a safety-razor, a blade seat comprising 25 a pair of opposed and relatively movable sections, a guard edge on each section, and blade stops on each guard edge; resilient means for normally holding said sections together, means for spreading said sections, a seat cover for clamping a double-edged blade to the seat while the sections are spread, and a plug carried by 30 the cover and adapted to remain in a plugging

position between the spread sections until the clamping has been accomplished.

3. In a safety-razor, a blade seat comprising 5 a pair of opposed and relatively movable sections, a guard edge on each section, and blade stops on each guard edge; resilient means for normally holding said sections together, means for spreading said sections, a seat cover for 10 clamping a double-edged blade to the seat while the sections are spread, and a plug carried by the cover and adapted to remain in a plugging position between the spread sections until the clamping has been accomplished; said plug having a portion which locks beneath the seat after 15 the sections have re-closed, whereby the cover is locked to the seat.

4. In a safety-razor, a curved blade seat comprising 20 a pair of opposed and relatively movable sections, a guard edge on each section, and blade stops on each guard edge; resilient means for normally holding said sections together, means for spreading said sections, means for 25 flexing a double-edged blade into conformity with the curvature of the seat while the sections are spread, and means for locking said sections in spread relationship until the flexing has been accomplished, said last-named means comprising a plug carried by the flexing means and adapted to enter the space between said sections.

MARCUS B. BEHRMAN. 30
